UNITED STATES PATENT OFFICE

ALBERT M. MASTERS, OF FRANKFORD, PHILADELPHIA, PENNSYLVANIA, ASSIGNOR TO
MASTERS STEEL FRAME COMPANY, OF PHILADELPHIA, PENNSYLVANIA, A COR-
PORATION OF DELAWARE

BLACKBOARD-FRAME MOUNTING

Application filed April 23, 1928. Serial No. 272,230.

The present invention relates to an improved blackboard frame mounting, the purpose of which is to provide a device of this kind, constructed to removably clamp and support the blackboard in position.

In order to accomplish this, it is the purpose to provide upper and lower sheet metal channel members for the reception of the board, clamps fulcrumed on adjusting screws 10 to force the board toward the outer flanges of the channels and clamp the same in position, there being suitable felt pads on opposite sides of the board where it is clamped, to prevent breaking of the board.

Another feature of the invention consists of longitudinal depressions in the back walls of the channels to steady and insure positioning the adjusting screws, in combination with a flange or other support forming a 20 part of the lower channel, to support the board.

A further feature of the invention consists in forming the lower channel with a chalk and eraser trough, said trough forming a 25 part of the lower channel.

It is to be understood that the particulars herein given are in no way limitative, and that while still keeping within the scope of the invention, any desired modification of 30 details and proportions may be made in the construction of the appliance according to circumstances.

The invention comprises further features and combination of parts to be hereinafter 35 set forth, shown in the drawings and claimed.

In the drawings:

Figure 1—is a view in front elevation of 40 a blackboard frame mounting constructed in accordance of the invention.

Figure 2—is a sectional view on line 2—2 of Figure 1, showing the blackboard in position, and the clamping means tightened.

Figure 3—is a detailed view in perspective 45 of one of the upper clamps in the upper channel.

Figure 4—is a sectional view similar to Figure 2, but showing the clamps loosened.

Figure 5—is a detailed perspective view 50 of the upper channel.

Figure 6—is a detailed perspective view of the lower channel.

Referring to the drawings, 1 identifies parts of the wall construction of a room and 2 and 3 are upper and lower channels for the 55 support of a blackboard 4.

The upper channel is constructed of sheet metal and has a fibre filler 5, suitable screws 6 passing through the channel and through the filler to hold the channel in place, the 60 screw entering the upper part of the wall 1.

The outer thickness of the channel has a longitudinal shoulder 7. The shoulder 7, though it may not support the part 18 of the jaw member 10 of the upper clamp, it does 65 act as an abutment for the part 18 during its sliding action on the outer wall or thickness of the channel, provided the clamp member is tightened sufficiently to draw the clamp member toward the outer wall of the channel. 70

Furthermore the shoulder or bend 7 of the outer wall of the channel permits the outer wall to yield more readily than it would if the shoulder or bend 7 did not exist. The reason for providing yieldability, is to permit 75 the blackboard to give uniformly throughout its area. For example if the blackboard 4 should be held rigid at its marginal edges with nothing behind the center of the board, the board would tend to yield in

the center and if the pressure should be sufficient the board would crack, hence by yieldably supporting the marginal edges of the board, the board may yield substantially and with uniformity throughout its entire area, 80 and such yieldability is considerably assisted by the paddings 11 and 12.

The inner thickness of the channel 2 has a longitudinal groove 8 for the reception of the ends of the screws 9, which pass through the outer thickness of the channel. This 85 groove is provided to prevent displacement of the screws laterally.

The screws 9 pass through the clamps 10, which by tightening up on the screws engage 90 tight against the blackboard at its upper portion and tighten it or force it against the outer thickness of the channel, there being felt padding 11 and 12 on either side of the blackboard, to prevent the metal from com- 95

100

ing in contact with the board which is preferably made of slate or any other suitable material, hence preventing the blackboard from cracking and to insure holding the black board firm, it being obvious that the outer wall of the channel at a point below the filler more or less gives as pressure is applied to the blackboard when writing and especially when erasing or otherwise cleaning the blackboard. The outer thickness of the channel has an internal flange 13 so as to more or less space the blackboard inwardly.

The lower channel 3 is somewhat similar to the upper channel, but with variations such as forming the outer thickness of the channel with a chalk or eraser receiving trough 14. The outer thickness of the channel 3 also has a longitudinal shoulder 15, as well as the inner thickness of the channel 3 having a longitudinal groove 16 which and the shoulder 15 perform the same function as the corresponding parts on the channel 2. Furthermore the outer thickness of the channel 3 has its inturned flange 13a provided with a laterally inward turned flange 17 on which the lower edge of the blackboard 4 rests.

With these exceptions, as previously stated the lower channel 3 and its attendant parts as well as the clamps substantially correspond with similar features of the channel 2, therefore the same reference characters apply.

The clamps 10 in each instance are substantially angular, and their shorter ends 18 have a moving fulcrum or bearing on the outer thickness of the channels, enabling the screws 9 when tightened to cause the clamps to rock and thereby draw the clamps tight against the blackboard.

The screws 9 above and below carry nuts 9a, and the edges of these nuts cooperate with shoulders 10a on the clamps 10 in such manner as to prevent the nuts from turning, when the screws 9 are tightened or loosened, so as to draw the clamps and their felt pieces 11 toward the blackboard. The felt pieces 11 are adhesively fastened to the clamps, while the felt strips 12 are adhesively fastened to the flanges 13 and 13a and extend longitudinally thereof. The flanges 13 and 13a have reasonable resiliency, so as to provide for a yieldable joint between the flanges and the blackboard and the blackboard and the clamps. It is a well established fact, and has been for years, that slate blackboard sections or slabs when split from the large blocks mined at the quarry are of varying thickness; that is, thicker at one end or one side than at the other end or other side, or possibly thicker in the middle. It has also been customary in constructing slate blackboard slabs to surface only one face, in which case the slate blackboard slabs still remain thicker at one end or one side than at an opposite end or opposite

side. In view of this, there has been difficulty in mounting the slate blackboard slabs, so as to arrange the slabs in order that their surfaced faces are all flush, particularly at the joints between the slabs, necessitating 70 wedges and the like to force the slabs into position so that their finished faces are all flush.

In view of these facts, one of the essential purposes of the present invention is to provide an improved mounting, wherein the 75 marginal clamping means include individual clamping jaws adjacent the rear uneven and unfinished faces of the slate blackboard slabs, the construction and arrangement of the marginal clamp being such that the individual clamping jaws adjacent the uneven 80 rough rear faces of the slabs are capable of adjustment from the front of the blackboard, whereas in the mounting of other slabs, such as glass slabs in store show windows and the like, the clamps can be adjusted and applied in position from the interior, as well as from the exterior, preferably from the interior. The record of this application will show that it has been a customary practice to use slate 85 blackboard slabs of varying thicknesses, evidence of this fact having been made of record in the application.

The invention having been set forth, what is claimed is:

1. In a blackboard frame mounting, the combination with upper and lower channels provided with means for fastening the channels to a stationary support, said channels having inner and outer yieldable walls, the 100 outer wall constituting a jaw member of a clamp, of an element constituting a second jaw member of said clamp and having a sliding fulcrum on the first jaw member, said clamp adapted to support a blackboard inter- 105 posed between the two jaw members, said first jaw member engaging the blackboard immediately just past the edge of the blackboard to hold the latter, and means passing through the first jaw member and operatively 110 connecting with the intermediate jaw member for tightening the intermediate member against the blackboard, said intermediate jaw member reaching materially farther toward the center of the blackboard than the outer 115 jaw member, the marginal edges of the outer walls merely extending past the edge of the blackboard far enough to hold the board but not far enough to limit the amount of writing surface of the board.

2. In a blackboard frame mounting, the combination with upper and lower channels provided with means for fastening the channels to a stationary support, said channels having inner and outer walls, each outer wall 125 constituting a jaw member of a clamp, of an element constituting a second jaw member of said clamp and being operatively mounted intermediate the inner and outer walls, said clamp adapted to support a blackboard inter- 130

- posed and clamped between the outer wall and said element, the outer walls engaging the blackboard immediately just past the edges of the blackboard to hold the latter, 5 means passing through the outer walls and operatively connected with the intermediate elements for tightening said jaw members against the blackboard, the outer wall of the lower channel terminating in a lateral flange 10 acting as a support with which the blackboard engages to support the board and prevent downward movement.
3. In a blackboard frame mounting, the combination with upper and lower channels 15 provided with means for fastening the channels to a stationary support, said channels having inner and outer walls, each outer wall constituting a jaw member of a clamp, of an element constituting a second jaw member of 20 said clamp and being operatively mounted intermediate the inner and outer walls, said clamp adapted to support a blackboard interposed and clamped between the outer wall and said element, the outer walls engaging 25 the blackboard immediately just past the edges of the blackboard to hold the latter, means passing through the outer walls and operatively connected with the intermediate elements for tightening said jaw members 30 against the blackboard, said second intermediate jaw members engaging with the blackboard and reaching materially farther toward the center of the blackboard than the outer walls, the marginal edges of the outer 35 walls merely extending past the marginal edge of the blackboard far enough to hold the board but not far enough to limit the amount of writing surface of the board.
4. In a blackboard frame mounting, the combination with upper and lower channels 40 provided with means for fastening the channels to a stationary support, said channels having inner and outer walls, each outer wall constituting a jaw member of a clamp, of an element constituting a second jaw member of 45 said clamp and being operatively mounted intermediate the inner and outer walls, said clamp adapted to support a blackboard interposed and clamped between the outer wall and said element, the outer walls engaging the blackboard immediately just past the edges of the blackboard to hold the latter, means passing through the outer walls and operatively connected with the intermediate 50 elements for tightening said jaw members against the blackboard, the outer wall of the lower channel terminating in a lateral flange acting as a support with which the blackboard engages to support the board and prevent 55 downward movement thereof.
5. In a blackboard frame mounting, the combination with upper and lower channels 60 provided with means for fastening the same to a stationary support, said channels having inner and outer walls, each outer wall constituting a jaw member of a clamp, of an element constituting a second jaw member of 65 said clamp and being located intermediate the inner and outer walls, both of said elements having sliding fulcrums on the outer walls, said clamp adapted to support a blackboard interposed and clamped between both sets of jaw members, screws passing through the outer walls and operatively connecting with the second jaw members for tightening them against the blackboard, and abutment means carried by the outer walls and cooperating with the intermediate elements for 70 limiting the sliding fulcrums of said second jaw members.
6. In a blackboard frame mounting, the combination with upper and lower channels 75 provided with means for fastening the same to a stationary support, said channels having inner and outer walls, each outer wall constituting a jaw member of a clamp, of an element constituting a second jaw member of 80 said clamp and being located intermediate the inner and outer walls, both of said elements having sliding fulcrums on the outer walls, said clamp adapted to support a blackboard interposed and clamped between both sets of jaw members, screws passing through the outer walls and operatively connecting with the second jaw members for tightening them against the blackboard, and abutment means carried by the outer walls and cooperating with the intermediate elements for 85 limiting the sliding fulcrums of said second jaw members.
7. In a blackboard frame mounting, the combination with upper and lower channels 90 provided with means for fastening the same to a stationary support, said channels having inner and outer walls, each outer wall constituting a jaw member of a clamp, of an element constituting a second jaw member of 95 said clamp and being located intermediate the inner and outer walls, both of said elements having sliding fulcrums on the outer walls, said clamp adapted to support a blackboard interposed and clamped between both sets of jaw members, screws passing through the outer walls and operatively connecting with the second jaw members for tightening them against the blackboard, and abutment 100 means carried by the outer walls and cooperating with the intermediate elements for limiting the sliding fulcrums of said second jaw members.
8. In a blackboard frame mounting, the combination with upper and lower channels 105 provided with means for fastening the same to a stationary support, said channels having inner and outer walls, each outer wall constituting a jaw member of a clamp, of an element constituting a second jaw member of 110 said clamp and being located intermediate the inner and outer walls, both of said elements having sliding fulcrums on the outer walls, said clamp adapted to support a blackboard interposed and clamped between both sets of jaw members, screws passing through the outer walls and operatively connecting with the second jaw members for tightening them against the blackboard, and abutment 115 means carried by the outer walls and cooperating with the intermediate elements for limiting the sliding fulcrums of said second jaw members.
9. In a blackboard frame mounting, the combination with upper and lower channels 120 provided with means for fastening the same to a stationary support, said channels having inner and outer walls, each outer wall constituting a jaw member of a clamp, of an element constituting a second jaw member of 125 said clamp and being located intermediate the inner and outer walls, both of said elements having sliding fulcrums on the outer walls, said clamp adapted to support a blackboard interposed and clamped between both sets of jaw members, screws passing through the outer walls and operatively connecting with the second jaw members for tightening them against the blackboard, and abutment means carried by the outer walls and cooperating with the intermediate elements for 130

limiting the sliding fulcrums of said second jaw members, both intermediate jaw members engaging with the blackboard and reaching materially farther toward the center of the blackboard than the outer walls, the marginal edges of the outer walls merely extending past the marginal edges of the board far enough to hold the board but not far enough to limit the amount of writing surface of the board.

8. In a blackboard frame mounting, the combination with upper and lower channels provided with means for fastening the same to a stationary support, said channels having inner and outer walls, each outer wall constituting a jaw member of a clamp, of an element constituting a second jaw member of said clamp and being located intermediate the inner and outer walls, both of said elements having sliding fulcrums on the outer walls, said clamp adapted to support a blackboard interposed and clamped between both sets of jaw members, screws passing through the outer walls and operatively connecting with the second jaw members for tightening them against the blackboard, and abutment means carried by the outer walls and cooperating with the intermediate elements for limiting the sliding fulcrums of said second jaw members, both intermediate jaw members engaging with the blackboard and reaching materially farther toward the center of the blackboard than the outer walls, the marginal edges of the outer walls merely extending past the marginal edges of the board far enough to hold the board but not far enough to limit the amount of writing surface of the board, the outer wall of the lower channel being outwardly bent on itself, thereby causing a chalk and eraser trough to be formed thereon.

9. In a blackboard frame mounting, upper and lower channels having fillers and provided with means for securing the channels to a stationary support, said channels having inner and outer yieldable walls extending beyond the fillers, each of the outer walls constituting a jaw member of a clamp, an element operatively supported intermediate the inner and outer walls of both channels and associated with an outer wall and thereby constituting a second jaw member of said clamp, both of said second jaw members operatively connecting with the inner and outer walls, thereby permitting the inner and outer walls of both channels to yield, said clamp adapted to support a blackboard interposed between the outer walls and the second jaw members, and devices passing through the outer walls and through the second jaw members, with means on said devices and cooperating with the second jaw members to tighten them into position.

10. In a blackboard frame mounting, upper and lower channels having fillers and pro-

vided with means for securing the channels to a stationary support, said channels having inner and outer yieldable walls extending beyond the fillers, each of the outer walls constituting a jaw member of a clamp, an element operatively supported intermediate the inner and outer walls of both channels and associated with an outer wall and thereby constituting a second jaw member of said clamp, both of said second jaw members operatively connecting with the inner and outer walls, thereby permitting the inner and outer walls of both channels to yield, said clamp adapted to support a blackboard interposed between the outer walls and the second jaw members, and screws passing through the outer walls and through the second jaw members, nuts on said screws and cooperating with the second jaw members to tighten them in position.

11. In a blackboard frame mounting, upper and lower channels having fillers and provided with means for securing the channels to a stationary support, said channels having inner and outer yieldable walls extending beyond the fillers, each of the outer walls constituting a jaw member of a clamp, an element operatively supported intermediate the inner and outer walls of both channels and associated with an outer wall and thereby constituting a second jaw member of said clamp, both of said second jaw members operatively connecting with the inner and outer walls, thereby permitting the inner and outer walls of both channels to yield, said clamp adapted to support a blackboard interposed between the outer walls and the second jaw members, and screws passing through the outer walls and through the second jaw members, nuts on said screws and cooperating with the second jaw members to tighten them in position, said second jaw members having means cooperating with the nuts to prevent movement thereof.

12. In a blackboard frame mounting, upper and lower channels having fillers and provided with means for securing the channels to a stationary support, said channels having inner and outer yieldable walls extending beyond the fillers, each of the outer walls constituting a jaw member of a clamp, an element operatively supported intermediate the inner and outer walls of both channels and associated with an outer wall and thereby constituting a second jaw member of said clamp, both of said second jaw members operatively connecting with the inner and outer walls, thereby permitting the inner and outer walls of both channels to yield, said clamp adapted to support a blackboard interposed between the outer walls and the second jaw members, and screws passing through the outer walls and through the second jaw members, nuts on said screws and

- cooperating with the second jaw members to tighten them in position, said second jaw members having means cooperating with the nuts to prevent movement thereof, the inner walls of both channels having means with which the screws engage to hold the screws straight when adjusted. 5
13. In a blackboard frame mounting, the combination with upper and lower channels 10 provided with means for fastening the channels to a stationary support, said channels having inner and outer walls, each outer wall constituting a jaw member of a clamp, of an element constituting a second jaw member of said clamp and being operatively mounted intermediate the inner and outer walls, said clamp adapted to support a blackboard interposed and clamped between the outer wall and said element, the outer walls 15 engaging the blackboard immediately just past the edges of the blackboard to hold the latter, means passing through the outer walls and operatively connected with the intermediate elements for tightening said jaw members against the blackboard, the outer wall of the lower channel terminating in a lateral flange acting as a support with which the blackboard engages to support the board and prevent downward movement, the outer walls 20 of both channels and the second jaw members having their adjacent faces padded for engagement with said blackboard. 25
14. In a blackboard frame mounting, upper and lower channels provided with means 30 for securing the channels to a stationary support, said channels having inner and outer yieldable walls, each of said outer walls constituting a jaw member of a clamp, an element located intermediate the inner and outer 35 walls and operatively associated with each of the outer walls, and constituting a second jaw member of said clamp, said clamp adapted to support a blackboard interposed between the outer walls and the second jaw members, the outer walls and said second jaw 40 members having their adjacent faces provided with cushions for engagement with the blackboard, means operatively connecting the outer walls and said second jaw members 45 to clamp the board in position, said connecting means operatively engaging with the inner walls for yieldably supporting the blackboard. 50
15. In a blackboard frame mounting, upper and lower channels provided with means 55 for securing the channels to a stationary support, said channels having inner and outer yieldable walls, each of said outer walls constituting a jaw member of a clamp, an element located intermediate the inner and outer 60 walls and operatively associated with each of the outer walls, and constituting a second jaw member of said clamp, said clamp adapted to support a blackboard interposed between the outer walls and the second jaw members, the outer walls and said second jaw 65 members having their adjacent faces provided with cushions for engagement with the blackboard, means operatively connecting the outer walls and said second jaw members to clamp the board in position, said connecting means operatively engaging with the inner walls for yieldably supporting the blackboard, the outer wall of the lower channel having a lateral flange with which the blackboard engages to support and prevent downward movement of same, both of said 70 second jaw members reaching materially far- 75
16. In a blackboard frame mounting, upper and lower channels provided with means for securing the channels to a stationary support, said channels having inner and outer yieldable walls, each of said outer walls constituting a jaw member of a clamp, an element located intermediate the inner and outer walls and operatively associated with each of the outer walls, and constituting a second jaw member of said clamp, said clamp adapted to support a blackboard interposed between the outer walls and the second jaw members, the outer walls and said second jaw 80 members having their adjacent faces provided with cushions for engagement with the blackboard, means operatively connecting the outer walls and said second jaw members to clamp the board in position, said connecting means operatively engaging with the inner walls for yieldably supporting the blackboard, both of said second jaw members reaching materially farther toward the center of the blackboard than the outer walls, the marginal edges of the outer walls merely extending past the marginal edge of the blackboard far enough to hold the board but not far enough to limit the amount of writing surface of the board. 85
17. In a blackboard frame mounting, upper and lower channels provided with means for securing the channels to a stationary support, said channels having inner and outer yieldable walls, each of said outer walls constituting a jaw member of a clamp, an element located intermediate the inner and outer walls and operatively associated with each of the outer walls, and constituting a second jaw member of said clamp, said clamp adapted to support a blackboard interposed between the outer walls and the second jaw members, the outer walls and said second jaw 90 members having their adjacent faces provided with cushions for engagement with the blackboard, means operatively connecting the outer walls and said second jaw members to clamp the board in position, said connecting means operatively engaging with the inner walls for yieldably supporting the blackboard, the outer wall of the lower channel having a lateral flange with which the blackboard engages to support and prevent downward movement of same. 95
18. In a blackboard frame mounting, upper and lower channels provided with means for securing the channels to a stationary support, said channels having inner and outer yieldable walls, each of said outer walls constituting a jaw member of a clamp, an element located intermediate the inner and outer walls and operatively associated with each of the outer walls, and constituting a second jaw member of said clamp, said clamp adapted to support a blackboard interposed between the outer walls and the second jaw members, the outer walls and said second jaw 100 members having their adjacent faces provided with cushions for engagement with the blackboard, means operatively connecting the outer walls and said second jaw members to clamp the board in position, said connecting means operatively engaging with the inner walls for yieldably supporting the blackboard, the outer wall of the lower channel having a lateral flange with which the blackboard engages to support and prevent downward movement of same. 105
19. In a blackboard frame mounting, upper and lower channels provided with means for securing the channels to a stationary support, said channels having inner and outer yieldable walls, each of said outer walls constituting a jaw member of a clamp, an element located intermediate the inner and outer walls and operatively associated with each of the outer walls, and constituting a second jaw member of said clamp, said clamp adapted to support a blackboard interposed between the outer walls and the second jaw members, the outer walls and said second jaw 110 members having their adjacent faces provided with cushions for engagement with the blackboard, means operatively connecting the outer walls and said second jaw members to clamp the board in position, said connecting means operatively engaging with the inner walls for yieldably supporting the blackboard, the outer wall of the lower channel having a lateral flange with which the blackboard engages to support and prevent downward movement of same. 115
20. In a blackboard frame mounting, upper and lower channels provided with means for securing the channels to a stationary support, said channels having inner and outer yieldable walls, each of said outer walls constituting a jaw member of a clamp, an element located intermediate the inner and outer walls and operatively associated with each of the outer walls, and constituting a second jaw member of said clamp, said clamp adapted to support a blackboard interposed between the outer walls and the second jaw members, the outer walls and said second jaw 120 members having their adjacent faces provided with cushions for engagement with the blackboard, means operatively connecting the outer walls and said second jaw members to clamp the board in position, said connecting means operatively engaging with the inner walls for yieldably supporting the blackboard, the outer wall of the lower channel having a lateral flange with which the blackboard engages to support and prevent downward movement of same, both of said second jaw members reaching materially far- 125
21. In a blackboard frame mounting, upper and lower channels provided with means for securing the channels to a stationary support, said channels having inner and outer yieldable walls, each of said outer walls constituting a jaw member of a clamp, an element located intermediate the inner and outer walls and operatively associated with each of the outer walls, and constituting a second jaw member of said clamp, said clamp adapted to support a blackboard interposed between the outer walls and the second jaw members, the outer walls and said second jaw 130 members having their adjacent faces provided with cushions for engagement with the blackboard, means operatively connecting the outer walls and said second jaw members to clamp the board in position, said connecting means operatively engaging with the inner walls for yieldably supporting the blackboard, both of said second jaw members reaching materially far-

ther toward the center of the blackboard than the outer walls, the marginal edges of the outer walls merely extending past the marginal edge of the blackboard far enough to hold the board but not far enough to limit the amount of writing surface of the board.

18. In a blackboard frame mounting, an outer continuous marginal clamping element, a plurality of slate blackboard sections to be arranged adjacent to and back of said element, the lower margin of said element having means to support each section, with the surfaced faces of the sections engaging the marginal portion of the element, and a plurality of individual clamping elements arranged at infrequent intervals and adapted to engage with the inner rear uneven faces of the slate blackboard sections, thereby keeping the outer faces of the sections flush and even throughout their entire area and at the joints, and means operable from the front of the blackboard for connecting the individual clamping elements to the continuous marginal clamping element.

19. A blackboard frame mounting, comprising an outer continuous marginal frame constituting one element of a clamp, said clamp adapted to support a plurality of slate blackboard sections adjacent and to the rear and engaged with said element, a plurality of individual clamping jaw elements adjacent to and cooperative with the rear uneven faces of the blackboard sections, and thereby holding the outer faces of such sections flush against the first element, and means connecting the individual clamping jaw elements with the first element, said connecting means being operable from the front of the blackboard to tighten the individual clamping jaw elements against the inner uneven faces of the blackboard sections.

20. A blackboard frame mounting, comprising an outer continuous marginal frame constituting one element of a clamp, said clamp adapted to support a plurality of slate blackboard sections adjacent and to the rear and engaged with said element, a plurality of individual clamping jaw elements adjacent to and cooperative with the rear uneven faces of the blackboard sections, said individual clamping jaw elements having sliding fulcrums on and cooperative with the first element and engaging the rear uneven faces of the blackboard sections to retain the sections with their outer finished surfaces flush, and means connecting the individual jaw elements to the first element, said means being adjustable to increase and decrease the pressure of the individual jaw elements against the blackboard sections.

21. A blackboard frame mounting comprising an outer continuous marginal frame constituting one element of a clamp, said clamp adapted to support a plurality of slate blackboard sections adjacent and to the rear and

engaged with said element, a plurality of individual clamping jaw elements adjacent to and cooperative with the rear uneven faces of the blackboard sections, said individual clamping jaw elements having sliding fulcrums on and cooperative with the first element and engaging the rear uneven faces of the blackboard sections to retain the sections with their outer finished surfaces flush, and means connecting the individual jaw elements to the first element, said means being adjustable to increase and decrease the pressure of the individual jaw elements against the blackboard sections, and abutment means carried by the first clamping element and cooperating with the individual jaw elements for limiting the sliding fulcrums of the individual jaw elements.

22. A blackboard frame mounting, comprising a frame of channel construction, having inner and outer walls, said outer wall constituting a jaw member of a clamp, a plurality of individual elements constituting opposing jaw members of said clamp and being located between the walls of the channel, said first jaw elements being marginally continuous, whereby the outer surfaced faces of the slate blackboard sections, which are adapted to be supported by said clamp, may assume even and flush positions adjacent the joints between the sections, and means passing through the outer walls of the frame and cooperative with the inner walls and connected operatively with the individual clamping elements for adjusting them in position according to the varying thicknesses of the blackboard sections.

23. A blackboard frame mounting, comprising a frame of channel construction having inner and outer walls, said outer wall constituting a jaw member of a clamp, a plurality of individual elements constituting opposing jaw members of said clamp and being located between the walls of the channel, said first jaw element being marginally continuous, whereby the outer surfaced faces of slate blackboard sections, which are adapted to be supported by said clamp, may assume even and flush positions adjacent the joints between the sections, and means passing through the outer walls of the frame and cooperative with the inner walls and connected operatively with the individual clamping elements for adjusting them in position according to the varying thicknesses of the blackboard sections, said individual clamping jaw elements having sliding fulcrums, and means cooperating with the individual clamping jaw elements for limiting the sliding fulcrums.

24. A blackboard frame mounting, comprising an outer continuous marginal frame constituting a continuous marginal jaw element of a clamp, the lower rail of said frame having means to support a plurality of slate

blackboard sections adapted to be supported by said clamp and having their outer faces surfaced and their inner faces rough and uneven, a plurality of individual elements constituting opposing jaw elements of said clamp and located in the rear of and engaging with the unfinished faces of said sections, and means for each individual second jaw member for clamping the same against the unfinished surfaces of said sections according to the varying thicknesses of the slate blackboard sections, whereby the finished surfaces of the sections may be held flush at their joints, and against the continuous marginal clamping jaw element.

25. A blackboard frame mounting, comprising an outer continuous marginal frame constituting a continuous marginal jaw element of a clamp, the lower rail of said frame having means to support a plurality of slate blackboard sections adapted to be supported by said clamp and having their outer faces surfaced and their inner faces rough and uneven, a plurality of individual elements constituting opposing jaw elements of said clamp and located in the rear of and engaging with the unfinished faces of said sections, and means for each individual second jaw member for clamping the same against the unfinished surfaces of said sections according to the varying thicknesses of the slate blackboard sections, whereby the finished surfaces of the sections may be held flush at their joints, and against the continuous marginal clamping jaw element, said means being carried by the continuous marginal jaw member, the upper rail of said frame extending far enough down below said means of the upper rail, whereby the blackboard sections may be inserted upwardly into said clamp, so that their lower ends may subsequently engage with said supporting means.

In testimony whereof he affixes his signature.

ALBERT M. MASTERS.
